UNITED STATES PATENT OFFICE.

JAMES RILEY, OF PARSONS, KANSAS.

ROUNDHOUSE EQUIPMENT.

1,109,017.

Specification of Letters Patent.

Patented Sept. 1, 1914.

Application filed March 13, 1914. Serial No. 824,574.

To all whom it may concern:

Be it known that I, JAMES RILEY, a resident of Parsons, in the county of Labette and State of Kansas, have invented certain new and useful Improvements in Round-house Equipments, of which the following is a full, clear, and exact description.

The invention relates to round-house equipments and more particularly to apparatus used for inducing draft in the locomotive furnaces to expedite the restoration of the locomotive to service condition after its fires have been banked.

In modern locomotive practice, a locomotive boiler is frequently washed out and refilled and also repaired when necessary, which usually necessitates putting out the fire in the fire box of the locomotive, and necessitates firing up the locomotive furnace to restore the locomotive to condition for road use. For the purpose of forcing combustion to a degree necessary to generate sufficient steam for road service of the locomotive, it has heretofore been proposed to employ apparatus including an exhauster, a main, connected to the inlet of the exhauster, and a series of branch pipes adapted to be connected to the stacks of all of the locomotives in the stalls of the round-house to induce draft in the boiler furnaces and to expedite combustion, for the purpose of quickly restoring the locomotive to condition for use on the road. In that apparatus, it has been found that a common exhauster for a number of locomotives does not attain a high degree of efficiency in the result sought and that such efficiency as could be attained was not economically effected; first, because the necessity for indirect piping, elbows and leaky joints between the stack-connections and the exhauster, reduced the draft and correspondingly lessened the efficiency in the draft induced through the furnaces of the locomotives; second, because a great amount of constantly available power was necessary to operate an exhauster of sufficient capacity for the number of locomotives which might simultaneously be connected to the apparatus; and third, because of the necessity of operating this exhauster of such capacity when but a single locomotive was connected to the apparatus.

An object of the present invention is to increase the efficiency of the exhausting apparatus in round-houses, to effect a substan-

tial saving of time in firing up the locomotive-boiler to restore it to condition for use by eliminating, so far as possible, all the joints and indirect connections between the stack of the locomotive and the exhauster, and by employing a separate or individual exhauster disposed for efficient results for each locomotive. By providing an equipment in which there is a substantially direct connection between the stack of the locomotive and the fan, in which joints are dispensed with as much as possible, the efficiency of the apparatus and the length of time necessary to promote sufficient combustion for road use of the locomotive, the length of time necessary for this operation is materially reduced and a material saving of time during which the locomotive remains out of use is effected. In practice, with the prior systems, a locomotive can be fired up in about fifty (50) minutes, while with the equipment embodying the present invention, locomotives have been fired up at an approximate average of thirty-two (32) minutes. By employing a separately operable unit for each stall comprising an exhauster and a direct connection between the exhauster and the locomotive stack, the exhauster and motor for driving it being only of sufficient capacity for inducing the draft through a single locomotive, the waste of power which results from the operation of an exhauster of sufficient capacity for a number of locomotives is avoided, because the motors and fans are only operated when necessary according to the number of locomotives being fired up. In practice, about five hundred (500) boiler horse power was required to operate an exhauster sufficient, at most, for four or five engines at a time when any number from one to five inclusive were being operated on, while in the practice of the present invention, a motor of about five (5) horse power has been found sufficient for each exhauster, and furthermore, only sufficient power necessary to operate the number of exhausters necessary in operation, corresponding to the number of locomotives being operated upon, was consumed.

The invention consists in the several novel features hereinafter set forth and more particularly defined by claims at the conclusion hereof.

In the drawings: Figure 1 is a plan of a portion of a round house equipped with the

invention. Fig. 2 is a side elevation of the apparatus for inducing the draft in one locomotive. Fig. 3 is an end elevation. Fig. 4 is a detail section, showing the pivotal connection for the swinging uptake-pipe. Fig. 5 is a detail section of the telescopic connection between the sections of the uptake-pipe.

The round-house A may be of usual construction and comprises a series of stalls, each of which is adapted for a locomotive and provided with a section of track a onto which the locomotive will be run into the round-house, as well understood in the art.

In the present invention, a separate or individual, complete exhausting apparatus and connection for a locomotive is provided for each stall in which locomotives are to be fired up. Each apparatus comprises an uptake, consisting of a pipe-section 10 having a flared hood 11 at the lower end thereof which is adapted to fit upon the top of a stack of a locomotive-boiler and a pipe-section 12, to which section 10 is telescopicly connected, to permit the hood 11 to be raised off or lowered onto the stack. If desired, counter-weights 14 on cables 15, passing around sheaves 16 and connected to hood 11, as at 17, may be employed to aid the operator in manipulating pipe-section 10 and hood 11.

The upper end of the uptake-pipe is provided with an elbow 18 which terminates in a screw-thread 19 which engages a collar 20 which is secured by bolts 21 to a short pipe 22 which is connected to and leads into the eye of an exhaust fan 24. This screw-thread permits the uptake pipe to be swung longitudinally of the track so that the hood 11 may be connected to the stack while the locomotive is in different positions on the track, the pivotal point or axis about which the uptake-pipe swings being substantially co-axial with the axis of the fan 24. A discharge stack or duct 27 extends upwardly from the outlet in the casing of the exhaust-fan 24. The fan-shaft 28 is directly connected to the shaft 29 of an electric motor 30 mounted on a base 31 at one side of the fan-casing. This motor drives the exhauster. For controlling the electric-circuit, in which the motor is included, an electric-switch 32 is mounted in the round-house adjacent the stall below the exhausting-apparatus, so that the operator can readily control the operation of the motor. The casing of the exhauster-fan 24 is supported by a suitable bracket 33 in which the short pipe 22 terminates. A protecting hood 34 is placed over the motor so that it will be protected from the elements. Bracket 33 and base 31 are secured to a suitable base-plate 35 which is mounted on the roof of the round-house adjacent the uptake-pipe.

In the operation of the apparatus, the

operator will swing the uptake-pipe longitudinally of the stall into position above the locomotive-stack according to its location on the track in the stall and lower the hood 11 onto the top of the stack. When a fire has been started in the fire box of the locomotive, switch 32 will be closed to cause the motor 30 to operate the exhauster-fan 24. This fan will produce a vacuum in the uptake pipe and in the flues of the locomotive boiler and cause air to be drawn through the fire-box to produce effective combustion and to exhaust the products of combustion through the uptake-pipe, the fan and the discharge-duct 27. When sufficient heat has been generated to produce sufficient steam for the operation of the locomotive, switch 32 will be opened to stop the motor 30 and fan 24, and the hood 11 will be then raised above the stack of the locomotive whereupon the locomotive may be run out of the round-house with its own power. If, at any time, there should be smoke in the round-house, or ventilation is desired, one or more of the fans 24 may be operated to discharge the smoke or air through the uptake and stack 27.

A characteristic of the apparatus set forth as an exemplification of the invention is that the products of combustion in the locomotive are conducted as directly as possible to the inlet-eye of the exhauster fan, which is conducive to high efficiency, particularly when first starting the fire, and the absence of unnecessary joints, connections and bends is a material factor of efficiency, so that a locomotive may be fired up sufficiently to put it in condition for use in a considerably shorter period than has been possible in any prior apparatus whereof I am aware. A characteristic of this equipment, in which there is a separately operable unit comprising an exhauster and stack-connection for each stall is, that it is possible to locate each exhauster in close proximity to the stack connection and thus eliminate indirect connections which have heretofore been deemed necessary. By providing a pipe which is pivoted co-axially with the pipe 22 leading to the fan or with the fan-shaft and so as to swing longitudinally of the stall or track in the stall, a single, simple, pivotal connection is sufficient to adapt the uptake pipe for connection to the stack at different points in the stall in connection with an adjustable hood 11. Furthermore, by providing a separate exhauster unit and connection and a motor for each stall, a very considerable saving in the power necessary to operate the exhauster is attained, it being necessary to use power only for those units actually required and only when required. Furthermore, more uniform efficiency is attained by separably operable units than is attained in a system where some of the stack-connec-

tions are connected to the exhauster more or less directly than others, because a greater efficiency is attained in that locomotive which offered the least resistance to the flow of air therethrough as a result of an indirect connection or leak in the system than in a locomotive which was more directly connected to the common exhauster. Furthermore, a leak in the apparatus at one point would decrease the efficiency of the entire apparatus in the prior systems, while a leak in an equipment of separably operable units will offset only one unit.

It will be observed that the swivel-joint 15 in the pipe connection between the stack and exhauster is one in which the movable and fixed members of the joint are co-axial so that the movable member may be rotated about the axis of the fixed member without 20 varying the direction of flow at the joint and without choking or restricting the flow. This type of joint dispenses with the necessity of flexible closures heretofore used in the apparatus in which the movable member 25 was pivoted to swing about an axis transverse to the axis of the movable member. Thus, the type of swivel-connection contributes materially to the efficiency of the apparatus while permitting adjustment of 30 the uptake-pipe, according to the location of the locomotive stack in the stall.

The invention thus exemplifies a round-house apparatus by which the locomotives may be fired up very quickly and which may 35 be economically operated.

The invention is not to be understood as restricted to the details set forth, since these may be modified within the scope of the appended claims, without departing from 40 the spirit and scope of the invention.

Having thus described the invention, what I claim as new and desire to secure by Letters Patent, is:

1. In a round house equipment, the combination of an exhauster having an inlet at one side thereof, an uptake pipe having a laterally extending terminal fixed thereon at its upper end, terminating and extending directly toward the inlet of the exhauster, and means at the lower end of the uptake pipe whereby it may be connected to the stack of a locomotive.

2. In a round house equipment, the combination of an exhauster having an inlet at one side thereof, means for driving said exhauster, an uptake-pipe having a laterally extending terminal fixed thereon at its upper end, and extending toward the inlet of the exhauster, and means at the lower end 55 of the uptake pipe whereby it may be connected to the stack of a locomotive, said uptake pipe being disposed adjacent the exhauster.

3. In a round-house equipment, the combination of an exhauster having an inlet at

one side thereof, means for driving said exhauster, an uptake pipe having a laterally extending elbow fixed thereon at its upper end, the exit end of said elbow being substantially co-axial with the inlet of the exhauster, and means at the lower end of said pipe whereby it may be connected to the stack of a locomotive.

4. In a round-house equipment, the combination of an exhauster having an inlet at one side thereof, means for driving said exhauster, an uptake pipe having a laterally extending elbow fixed thereon at its upper end, the exit end of said elbow being substantially co-axial with the inlet of the exhauster, and means at the lower end of said pipe whereby it may be connected to the stack of a locomotive, said elbow being disposed adjacent the exhauster.

5. A round-house equipment, the combination of an exhauster having an inlet at one side thereof, means for driving said exhauster, an uptake pipe having a laterally extending terminal fixed thereon at its upper end and leading to said inlet, a swivel-connection which permits the pipe and said terminal to swing so the lower end of the pipe may be adjusted longitudinally of the stall, and means at the lower end of said pipe whereby it may be connected to the stack of a locomotive.

6. In a round-house equipment, the combination of an exhauster having an inlet at one side thereof, means for driving said exhauster, an uptake pipe having a laterally extending terminal fixed thereon at its upper end and leading to said inlet, a swivel-connection for the exit-end of said terminal which permits the pipe and said terminal to swing so the lower end of the pipe may be adjusted longitudinally of the stall, and means at the lower end of said pipe whereby it may be connected to the stack of a locomotive, said swivel-connection being disposed adjacent the inlet to the exhauster.

7. In a round-house equipment, the combination of an exhauster having an inlet at one side thereof, means for driving said exhauster, an uptake pipe having a laterally extending terminal at its upper ends, a swivel-connection for the upper end of said terminal which permits the pipe and said terminal to swing so the lower end of the uptake pipe may be adjusted longitudinally of the stall, and means at the lower end of said pipe whereby it may be connected to the stack of a locomotive, the axis of said swivel-connection extending directly toward the inlet of the exhauster.

8. In a round-house equipment, the combination of an exhauster having an inlet at one side thereof, means for driving said exhauster, an uptake pipe having a laterally extending terminal at its upper end, a swivel connection for the upper end of said termi-

nal which permits the pipe and said terminal to swing so the lower end of the uptake may be adjusted longitudinally of the stall and means at the lower end of said pipe whereby it may be connected to the stack of a locomotive, the axis of said connection extending directly toward the inlet of the exhauster, said connection being disposed adjacent the exhauster.

said pipe whereby it may be connected to the stack of a locomotive, the axis of said swivel connection being substantially horizontal and extending directly toward the inlet to the exhauster, said exhauster being disposed adjacent the swivel connection. 70

16 9. In a round-house equipment, the combination of an exhauster having an inlet at one side thereof, means for driving said exhauster, an uptake pipe having a laterally extending terminal at its upper end, a swivel-
15 connection for the upper end of ~~said~~ terminal which permits the pipe and said laterally extending terminal to swing so the lower end of the uptake may be adjusted longitudinally of the stall, and means at
20 the lower end of said pipe whereby it may be connected to the stack of a locomotive, the axis of said swivel-connection being substantially co-axial with the inlet to the exhauster.

13. In a round-house equipment, the combination of an exhauster having an inlet, means for driving said exhauster, and a pipe-connection having one of its ends adapted to be connected to the stack of a locomotive, and its other end connected to said inlet, said connection comprising a swivel joint having fixed and movable members which are co-axial so that the movable member thereof may be rotated around the coaxial point without varying the area of the duct or direction of flow at the joint.

25 10. In a round-house equipment, the combination of an exhauster having an inlet at one side thereof, means for driving said exhauster, an uptake pipe having a laterally extending terminal at its upper end, a
30 swivel-connection for the upper end of said terminal which permits the pipe and said terminal to swing so the lower end of the uptake may be adjusted longitudinally of the stall, and means at the lower end of said
35 pipe whereby it may be connected to the stack of a locomotive, the axis of said swivel-connection being substantially co-axial with the inlet to the exhauster, said swivel-connection being disposed adjacent the exhauster.

40

14. In a round-house equipment, the combination of an exhauster having an inlet, means for driving said exhauster, and a pipe connection connected to said inlet comprising an uptake having means at its lower end whereby it may be connected to the stack of a locomotive, and a swivel joint having fixed and movable members which are co-axial so that the movable member thereof may be rotated around the co-axial point without varying the direction of flow at the joint, said uptake being connected to said joint by an elbow, so that it may be swung longitudinally from the stall.

11. In a round house equipment, the combination of an exhauster having an inlet at one side thereof, means for driving said exhauster, an uptake pipe having a laterally extending terminal at its upper end, a swivel-connection for the upper end of said terminal which permits the pipe and said terminal to rotate so the lower end of the uptake may be adjusted longitudinally of the stall, and means at the lower end of said pipe whereby it may be connected to the stack of a locomotive, the axis of said swivel-connection being substantially horizontal and extending directly toward the inlet to the exhauster.

15. In a round-house equipment, the combination of an exhauster having an inlet, means for driving said exhauster, and a pipe-connection having one of its ends adapted to be connected to the stack of a locomotive, and its other end connected to said inlet, said connection comprising a swivel joint having fixed and movable members which are co-axial so that the movable member thereof may be rotated around the co-axial point without varying the area of the duct or direction of flow at the joint, said joint being disposed adjacent the exhauster. 110

12. In a round-house equipment, the combination of an exhaust having an inlet at one side thereof, means for driving said exhaust, an uptake-pipe having a laterally extending terminal at its upper end, a swivel connection for the upper end of said terminal which permits the pipe and said terminal to rotate so the lower end of the uptake pipe may be adjusted longitudinally of the stall, and means at the lower end of

16. In a round-house equipment, the combination of a plurality of separately operable exhausting units for the stalls respectively, each comprising an exhauster having an inlet, and a pipe connection connected to the inlet of the exhauster and adapted to be connected to the stack of a locomotive, means for separately operating the exhausters, and means for separately controlling the operation of the exhausters. 115 120

17. In a round-house equipment, the combination of a plurality of separately operable exhausting units, for the stalls respectively, each comprising an exhauster having an inlet and an uptake connected to the inlet of the exhauster and having means at its lower end adapted to be connected to the stack of a locomotive, means for separately driving the exhausters and means for

separately controlling the operation of the exhausters, each uptake being disposed adjacent to the exhauster to which it is connected.

18. In a round-house equipment, the combination of a plurality of separately operable exhausting units for the stalls respectively, each unit comprising an exhauster having an inlet and an adjustable pipe-connection connected to the inlet of the exhauster and adapted to be connected to the stack of a locomotive, means for separately operating the exhausters and means for separately controlling the operation of the exhausters.

19. In a round house equipment, the combination of a plurality of separately operable exhausting units for the stalls respectively, each unit comprising an exhauster and an adjustable uptake pipe connected to the inlet of the exhauster and adapted to be connected to the stack of a locomotive, means for separately operating the exhausters, and means for separately controlling the operation of the exhausters, each uptake being disposed adjacent to the exhauster to which it is connected.

20. In a round-house equipment, the combination of a plurality of separately operable exhauster units for the stalls respectively, each unit comprising an exhauster having an inlet, a pipe-connection connected to the exhauster and comprising an uptake having means at its lower end adapted to be connected to the stack of a locomotive, the upper end of the uptake having an elbow extending laterally and pivoted to swing about an axis extending directly toward the inlet to the exhauster, and means for separately driving the exhausters.

21. In a round-house equipment, the combination of a plurality of separately operable exhauster units, for the stalls respectively, each unit comprising an exhauster having an inlet, a pipe connection connected to the exhauster comprising an uptake having means at its lower end adapted to be connected to the stack of a locomotive, the upper end of the uptake having an elbow extending laterally therefrom and pivoted to swing about an axis substantially co-axial with the inlet to the exhauster, means for separately driving the exhausters, and means for separately controlling the operation of the exhausters.

22. In a round house equipment, the combination of a plurality of separately controlling exhausting units for the stalls respectively, each unit comprising an exhauster having an inlet at one side thereof, an uptake pipe having its lower end adapted to be connected to the stack of a locomotive and having an elbow at its upper end disposed adjacent to the exhauster and leading directly to said inlet, means for separately

driving the exhausters and means for separately controlling the operation of the exhausters.

23. In a round house equipment, the combination of a plurality of separately operable exhausting units for the stalls respectively, each unit comprising an exhauster disposed above a stall and having an inlet at one side thereof, an uptake pipe having a lower terminal adapted to be connected to the stack of a locomotive, an elbow at the upper end of said uptake, and a short pipe section extending directly between the elbow and said inlet, and means for separately driving and controlling exhausters.

24. In a round house equipment, the combination of a plurality of separately operable exhausting units for the stalls respectively, each unit comprising an exhauster disposed above a stall and having an inlet at one side thereof, and an uptake-pipe having its lower terminal adapted to be connected to the stack of a locomotive, an elbow at the upper end of said uptake, a short pipe-section extending directly between the elbow and said inlet, and means for separately driving the exhausters, said uptake and elbow being pivoted to swing about a point coaxial with said short pipe-section.

25. In a round house equipment, the combination of a plurality of separately operable exhausting units for the stalls respectively, each unit comprising an exhauster having an inlet, means for separately driving the exhausters, and a pipe-connection having one of its ends adapted to be connected to the stack of a locomotive and its other end connected to said inlet, said connection comprising a swivel joint having fixed and movable members which are co-axially connected and which remain co-axial when the movable member is rotated relatively to the other.

26. In a round-house equipment, the combination of a plurality of separately operable exhausting units for the stalls respectively, each unit comprising an exhauster having an inlet at one side thereof, an uptake pipe having its lower terminal adapted to be connected to the stack of a locomotive, an elbow fixed on the other end of the uptake connected to said inlet and a swivel joint at the end of said elbow, comprising a fixed member which is co-axial with one end of the elbow, said joint being formed so that the end of the elbow will remain co-axial with the fixed member.

27. In a round house equipment, the combination of an exhauster having an inlet at one side thereof, means for driving the exhauster, an uptake having its lower terminal adapted to be connected to the stack of a locomotive, an elbow at the upper end of the uptake, and a screw-threaded connection for the terminal of the elbow, arranged to

permit the lower end of the pipe to swing longitudinally of the stall.

28. In a round house equipment, the combination of an exhauster having an inlet at one side thereof, means for driving the exhauster, an uptake having its lower terminal adapted to be connected to the stack of a locomotive, an elbow at the upper end of the uptake, and a screw-threaded connection for

the terminal of the elbow, arranged to permit the lower end of the pipe to swing longitudinally of the stall, and a short pipe-section extending directly between the said elbow and the inlet to the exhauster.
